UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

ROOF STRUCTURE FOR RAILWAY CARS

Original application filed April 19, 1926, Serial No. 103,069. Divided and this application filed February 6, 1928. Serial No. 252,353.

My device relates to railway box cars and consists in providing means for moving heavy cargoes in and out of the car and to desired positions within the car.

It is common practice to throw a rope or chain over one of the carlines or purlins of a box car to raise the lading, but the ordinary roof frame of a car is not designed to resist the stresses imposed thereby, thus frequently causing distorted and leaky roofs.

One of the objects of the invention is to provide means for attaching a load lifting device which strengthens the roof member to which it is secured.

Another object of the invention is to locate means for attaching a load lifting device so that it is accessible from the inside of the car but does not reduce the free inside height of the car. Light packages and other commodities are sometimes loaded to the roof of the car; therefore, it is desirable to locate such means so as not to reduce the cubical capacity of the car.

In some cars the roof structure comprises carlines spanning the distance between the opposite side plates with metallic roof sheets spanning the space between the adjacent carlines. These roof sheets are sometimes secured to the carlines making what is known as a rigid roof and sometimes positioned loosely between the carlines making what is known as a flexible roof. Sometimes the carlines are eliminated and the roof sheets are so formed and perhaps strengthened that they perform the functions of the usual carline, so the term "carline" as used in this patent means that structure which performs the functions of a carline whether a separate member or an integral part of the sheet or sheets forming the roof proper of the car. My invention may be modified so that it will be applicable to any type of freight car roof.

In the drawings:

Fig. 1 shows a part of a railway car with my invention applied thereon.

Fig. 2 is a section on line 2—2 of Fig. 1. Fig. 3 is a section on line 3—3 of Fig. 2. Fig. 4 shows a modified form of the device. Fig. 5. is a section on line 5—5 of Fig. 4. Fig. 6 shows the device applied to a flexible type of roof.

Fig. 7 shows the device applied to another type of rigid roof.

Fig. 8 shows a method of reinforcing the carline where additional strength is required.

Figs. 9 and 10 show the device in detail. The drawings illustrate an all steel rigid roof wherein the carlines 2 have their extremities secured to the side plates 3 of the car. These carlines are of inverted channel section with spaced apart side walls 4—4, an upper portion 5, and laterally extending flanges 6. The roof sheets 7 span the distance between the opposite side plates or from one side plate to the ridge or center of the car. These roof sheets have upturned flanges 8 at their opposite sides which are secured to the opposite side walls 4 respectively of the car-line.

A device 10 is positioned entirely within the inverted channel and has its opposite ends secured to the opposite side walls of the carline and a space 11 is provided above the device 10 and below the upper portion 5 of the carline so that a load lifting device may be attached thereto by passing a rope or chain through this opening or passing the nose of the hook through it. Figs. 4 and 5 (and Fig. 6) show a modified form wherein the lower part of the device 30 is provided with oppositely projecting flanges 12 to accommodate ice tongs or other such load lifting devices, which device 30 is also provided with an upstanding web 31 which is provided with an aperture 32 through which a chain may be inserted; or in other words, this aperture performs the same function as the space 11 described above. Both the carline and the device are positioned entirely above the lower

surface 13 of the roof sheets so as not to interfere with the loading capacity of the car. This device also strengthens the carlines by acting as a spreader because when a channel section beam begins to deflect the opposite side walls 4-4 depart from their vertical plane, or in other words, the channel spreads apart or opens up, as it is called. The device is a strut-tie as it prevents the walls 4-4 of the channel from deflecting either toward or away from each other. This device, therefore, serves the dual purpose of strengthening the roof member to which it is secured and provides means for attaching a load lifting device. The device may be riveted into place with rivets of less shearing strength than the ultimate strength of the carline so that the device will be pulled away from the carline before the carline is distorted. This to minimize the damage when excessive loads are applied to the device.

The greater the inside height of the car the better, as the height from the rail is limited by the tunnel and bridge clearances, particularly at the eaves, therefore, a roof structure must be very shallow. In order to obtain the required strength for certain loads in such a shallow carline it may be necessary to provide other reinforcements. For such necessity I add the reinforcements 14 (see Fig. 8) which are located entirely within the inverted channel carline for reasons already enumerated.

Fig. 6 shows my invention applied to a flexible steel roof wherein the roof sheets 20 are spaced apart from the carline 21 and a cap 22 is used to weather-proof the space between the roof sheets and the carline.

Fig. 7 shows my invention applied to another type of rigid roof wherein the roof sheets 23-24 overlap the carline 25 and are secured thereto in rigid relation by a clamp or a rivet.

Fig. 8 shows a roof similar to the one shown in Fig. 2 and shows the reinforcing members 14 which also support the device 10.

Fig. 10 shows the device of Figs. 2 and 3 in detail.

Fig. 9 shows a modification of the device 50 wherein the central portion is made cylindrical.

The device may be secured to a carline and perform the advantageous functions enumerated herein or it may be secured to roof sheets 55 which are formed and arranged to serve as carlines and come within the scope of this invention.

The accompanying drawings illustrate the preferred form of the invention, though it 60 is to be understood that the invention is not limited to the exact details of construction shown and described, as it is obvious that various modifications thereof within the scope of the claims will occur to persons skilled in 65 the art.

This is a division of my co-pending application Serial No. 103,069, filed April 19, 1926.

I claim:

1. In a car roof construction, an inverted channel member with its extremities secured to the opposite side plates of the car, a roof sheet on each side of the member, and a device secured within the channel member and arranged to accommodate load lifting devices, both the member and the device being entirely above the lower surface of the roof sheets. 70

2. In a car roof construction, an inverted channel member with its extremities secured to the opposite side plates of the car, a roof sheet on each side of the member, and a device secured within the channel member to the opposite walls thereof and arranged to accommodate load lifting devices, both the member and the device being entirely above the lower surface of the roof sheets. 75

3. In a car roof construction, an inverted channel member with its extremities secured to the opposite side plates of the car, a roof sheet on each side of the member, and a device secured within the channel member so as to provide a space above said device, both the member and the device being entirely above the lower surface of the roof sheets. 80

4. In a car roof construction, an inverted channel member with its extremities secured to the opposite side plates of the car, a roof sheet on each side of the member, and a device secured within the channel member so as to provide a space above said device, said device having oppositely disposed flanges at its lower portion, both the member and the device being entirely above the lower surface of the roof sheets. 85

5. In a car roof construction, an inverted channel member with its extremities secured to the opposite side plates of the car, a roof sheet on each side of the member, and a device secured within the channel member to the opposite walls thereof so as to provide a space above said device, said device having oppositely disposed flanges at its lower portion, both the member and the device being entirely above the lower surface of the roof sheets. 90

6. In a car roof construction, an inverted channel member with its extremities secured to the opposite side plates of the car, a roof sheet on each side of the member extending within and secured to said member, and a device secured within the channel member and arranged to accommodate load lifting devices, both the member and the device being entirely above the lower surface of the roof sheets. 95

7. In a car roof construction, an inverted channel member with its extremities secured to the opposite side plates of the car, a roof sheet on each side of the member having upturned flanges at their sides secured to the 100

opposite walls of the member, and a device secured within the channel member and arranged to accommodate load lifting devices, both the member and the device being entirely above the lower surface of the roof sheets.

8. In a car roof construction, a member with its extremities secured to the opposite side plates of the car, a roof sheet on each side of the member, and a device supported by said member arranged to accommodate a load lifting device, both the member and the device being entirely above the lower surface of the roof sheets.
